UNITED STATES PATENT OFFICE.

EDMUND P. KINNE, OF ALLIANCE, OHIO, ASSIGNOR TO AMERICAN STEEL FOUNDRIES,
OF NEW YORK, N. Y., A CORPORATION OF NEW JERSEY.

DRAFT-RIGGING FOR PILOT-COUPINGS.

1,157,874.

Specification of Letters Patent.

Patented Oct. 26, 1915.

Application filed December 6, 1912. Serial No. 735,226.

To all whom it may concern:

Be it known that I, EDMUND P. KINNE, a citizen of the United States, and resident of Alliance, in the county of Stark and State of Ohio, have invented certain new and useful Improvements in Draft-Rigging for Pilot-Couplings, of which the following is a specification.

My invention relates to railway cars and 10 has particular reference to a novel draft rigging for application to pilot beams of engines.

It is the common practice to attach couplers to the pilot beams of locomotives without 15 interposing a draft gear, the connection being rigid with relation to longitudinal pull and buff but being pivoted in order to permit limited sidewise movement. Such an arrangement, however, throws excessive 20 strains on the coupler particularly in buffering and therefore the principal object of my invention is to provide a draft rigging for use in this connection.

It is desirable and not unusual to provide 25 an integral buffer beam with a recess in which the coupler is secured. Therefore another object of my invention is to provide a draft rigging which may be associated with such an integral beam without weakening 30 the beam. In my construction the draft rigging may be assembled and then inserted as a unit within the recess in the beam, being held in place by a removable key.

As above indicated it is desirable that the 35 coupler should be permitted limited sidewise movement and it is also desirable that the coupler should be automatically centered. I have provided such means in my 40 design.

The invention will be more readily understood by reference to the accompanying drawings, wherein,

Figure 1 is a plan section showing an 45 integral buffer beam and king-post casting within which my novel draft rigging is secured; Fig. 2 is an end elevation of the construction shown in Fig. 1; Fig. 3 is a longitudinal section through the center of the 50 construction shown in Fig. 1; Fig. 4 is a section on the line 4-4 of Fig. 3; Fig. 5 is a section on the line 5-5 of Fig. 3; Figs. 6, 7, 8 and 9 are perspective views of yoke, follower blocks, key and shim respectively 55 later to be described.

Referring more particularly to the drawings, it will be seen that I provide an integral buffer beam 10, combining therewith a king-post casting 11, having a king-bolt opening 12 therein. Within the combined 60 buffer and king-post castings, I provide a recess 13 within which the draft rigging is seated. This recess has no opening except that through the outer face of the beam 10, through which the shank of the coupler projects. Formed near the mouth of the recess 13 are vertical grooves 14, one on each side of the opening within which a U-shaped fastening key 15 is seated. It will be seen by reference to Figs. 1 and 2 that the 70 grooves 14 provide seats or bearings for the two legs of the U-shaped fastening member, the bearing being throughout practically the entire length of the key whereby a complete longitudinal shear would necessarily 75 be effected before the draft rigging could free itself. The buffer casting is provided at the top and bottom at a point contiguous to the recess 13 with lips or enlargements 16, 17. The cross bar of the fastening key 15 80 rests behind the upper enlargement 16, thus removing it from possibility of injury and providing greater resistance to displacement under longitudinal pull.

The coupler 18 herein shown, is provided 85 with a short shank 19, apertured to accommodate a pivot pin 20, having a large head 21. This pivot pin also cooperates with slots 22, formed in the longitudinal members of a primary yoke 23, which yoke is 90 best shown in Fig. 6. A transverse wall 24 is provided in the yoke against which the forward draft springs 25 abut. Draft springs 26 abut the rear vertical wall of the yoke. As best shown in Figs. 1, 3 and 7, I 95 provide novel front and rear follower blocks 27, 28, respectively. The forward block is provided with a front extension 29, of a width narrower than that of the block, thus providing shoulders 30, which shoulders 100 co-operate with the legs of the fastening key 15, as is clearly shown in Fig. 1. The extension 29 is squared and abuts the squared end of the shank 19. Thus it will be seen that while the coupler is permitted a limited sidewise rotation around the pivot pin 20, the squared end causes the recession of the front follower block 27 and the compression of the spring 25. Obviously also the draft yoke will be pulled forward thus 105 110

compressing the spring 26. Both the followers 27, 28, are provided with corresponding projections or legs which in the normal position are in contact as shown in Fig. 1. 5 This arrangement of followers and legs forms in effect a secondary or buffing yoke. In such position the inner face 31 of the rear follower 28 is held against the partition 24 in the yoke by the force of the spring 10 26; also the end wall of the yoke 23 is held against the walls formed as a part of the king-post casting 11. Thus under buff the force transmitted by the coupler shank 19 extends to the front follower 27, whereby 15 the spring 25 is compressed, then to the rear follower 28, through the coöperating legs on the two followers and the consequent compression of the spring 26. This requires that the pivot pin shall travel rearward in 20 the slot 22. On pull, the parts being in the position shown, the strain is transmitted to the yoke 23, and the followers being held against forward movement by means of the key 15, the springs 25, 26, are compressed 25 by reason of the partition 24 and the rear vertical wall of the yoke.

The coupler shank, as shown, is of a slightly less height than the space between the longitudinal members of the yoke 22, in 30 order that the height of the coupler may be adjusted as required. This I accomplish by means of the U-shaped shim 33, as best shown in Figs. 3 and 9, this shim being provided with upwardly projecting dowels 34, 35 which may be seated in the recesses 35, 36, in the upper and lower walls respectively of the yoke. Such a shim may be inserted from the mouth of the yoke, is held in place by means other than the pivot pin and may be 40 readily shifted as required.

It will be noted that the draft rigging, complete as shown, may be assembled apart from the car or locomotive, then placed in the recess 13, and the key 15 inserted. Furthermore, a coupler may be readily removed and replaced by another without disturbing other parts of the mechanism. The arrangement is extremely simple and rigid and provides a cushion for use on pilot beams of 45 locomotives in which practically all the advantages of the usual forms of tandem gear are secured as applied to railway cars.

It will be obvious that modifications may be made in the construction shown and such modifications as are within the scope of my 50 claims I consider within the spirit of my invention.

I claim:

1. A draft rigging for railway cars comprising, in combination, a yoke held against rearward movement, a coupler having a shank, a connection between said yoke and coupler whereby said coupler may move relatively to said yoke, a front follower within 55 said yoke and coöperating with said coupler

and provided with stop abutting shoulders, and a stop against which said shoulders abut, said stop acting as the sole means for retaining said draft rigging in place, substantially as described. 70

2. In a draft rigging, the combination of a yoke having an intermediate partition, a pair of followers integral longitudinally projecting side extensions the extension on one of said followers being adapted to embrace said intermediate partition, cushions carried by said yoke and coöperating with said followers, shoulders on said other follower, a key projecting into the path of said followers and adapted to abut the shoulders on said last-mentioned follower, and a coupler connected to said yoke and adapted for movement relative thereto, substantially as described. 75

3. In a device of the class described, the combination of a pilot beam having an open ended recess therein, a vertical flange projecting upwardly from said beam near the mouth of said recess, a draft rigging within said recess, and a U-shaped key adapted to 80 maintain said draft rigging within said recess, the horizontal member of said key being seated behind said vertical flange, substantially as described. 90

4. In a draft rigging for railway cars, the combination of a yoke having an intermediate partition, a coupler connected to said yoke, said connection permitting a relative sliding pivotal movement between said coupler and yoke, a pair of U-shaped followers within said yoke, the said followers abutting respectively the partition and coupler, one of said followers having stop abutting shoulders, and a stop adapted to coact with said shoulders to limit the movement of said follower in one direction, substantially as described. 95

5. In a draft rigging for railway cars, the combination of a yoke provided with an intermediate wall and having a sliding connection to a coupler shank, tandem arranged springs, a pair of U-shaped followers arranged transversely with respect to said yoke, the arms thereof abutting and the ends thereof in contact with said coupler and the said intermediate wall respectively, the said ends acting as followers for the said springs, and a stop member against which one of said followers abuts, substantially as described. 110

6. In a draft rigging for railway cars, the combination with a yoke provided with an intermediate wall and having a sliding connection with the coupler shank, tandem arranged springs, a pair of U-shaped followers arranged transversely with respect to said yoke, the arms thereof abutting and the ends thereof in contact with the said coupler and the said intermediate wall respectively, said ends acting as followers for said springs, and 115 120 125 130

a stop member against which one of said followers abuts, said stop member being vertically arranged with respect to said follower and acting to maintain the entire draft rigging in operative position, substantially as described.

7. In a draft rigging, the combination with a coupler shank, a yoke having a pin and slot connection with said shank whereby 10 said coupler is permitted a radial and sliding movement relative to said yoke, said yoke being provided with an intermediate wall, tandem arranged springs, a pair of U-shaped

followers arranged transversely with respect to said yoke, the ends thereof in contact with 15 said coupler and the said intermediate wall, the said ends acting as followers for said springs, and a stop member against which one of said followers abuts, said stop member comprising a vertically arranged U-shaped 20 member.

EDMUND P. KINNE.
